CLAIM

The ornamental design for a display screen with animated graphical user interface of a roulette game with a contrasting sector pulsing highlighting effect, as shown and described.

DESCRIPTION

FIG. 1 is a first image in a sequence for a display screen with an animated graphical user interface of a roulette game with a contrasting sector pulsing highlighting effect showing our new design;

FIG. 2 is a second image thereof;

FIG. 3 is the third image thereof;

FIG. 4 is the fourth image thereof;

FIG. 5 is the fifth image thereof;

FIG. 6 is the sixth image thereof;

FIG. 7 is the seventh image thereof;

FIG. 8 is the eighth image thereof;

FIG. 9 is the ninth image thereof;

FIG. 10 is the tenth image thereof;

FIG. 11 is the eleventh image thereof; and,

FIG. 12 is the twelfth image thereof.

The peripheral broken line represents a boundary of the display screen with graphical user interface and forms no part of the claimed design. The broken line showing of the number and other features within the disclaimed peripheral boundary forms no part of the claimed design. The contrast in grayscale representation in the different sectors represents a contrast in highlighting effect which pulses in the animation. The appearance of the graphical user interface sequentially transitions between the images shown in FIGS. 1-12. The process or period in which one image transitions to another forms no part of the claimed design.
